UNITED STATES PATENT OFFICE.

CHARLES A. CANNON AND HARVEY E. SCOTT, OF McNAB, ARKANSAS.

FIRE-SCREEN.

1,388,095.

Specification of Letters Patent. Patented Aug. 16, 1921.

Application filed August 23, 1918. Serial No. 251,170.

To all whom it may concern:

Be it known that we, CHARLES A. CANNON and HARVEY E. SCOTT, citizens of the United States, residing at McNab, in the county of 5 Hempstead and State of Arkansas, have invented new and useful Improvements in Fire-Screens, of which the following is a specification.

This invention has reference to a fire 10 screen.

An object of the invention is to produce a folding fire screen that may be easily and quickly attached to the front of an open fireplace to prevent sparks or live coals from 15 being thrown out of the fire upon the floor as well as to effectively protect the wooden mantel which is secured to the fireplace, the said device, when not in use, being folded into a small compact structure, and swung 20 above the fireplace opening beneath the mantel and latched in such position.

A further object of the invention is to produce a screen for fireplaces that, in its operative position is set up to provide a rectangular construction disposed outward of 25 the fireplace, the same being constructed of hinged sections foldable one on the other and hingedly connected to the fireplace whereby the said sections may be swung 30 against the said fireplace upward of the opening therein and latched thereto.

It is a further object of the invention to produce a device of this character which will not detract from the appearance of the 35 fireplace, but as a matter of fact will additionally ornament the same, the construction being extremely simple and cheaply manufactured, readily arranged to screen the fire and readily folded and sustained above the 40 fireplace opening when not in use.

The foregoing objects and others which will appear as the nature of the invention is better understood may be accomplished by a construction, combination and operative 45 arrangement of parts such as illustrated by the accompanying drawings, in which:

Figure 1 is a perspective view of a fireplace showing the improved folding screen applied thereto and illustrated in operative 50 position;

Fig. 2 is a transverse sectional view of the parts illustrated in Fig. 1;

Fig. 3 is a front elevation showing the screen folded and supported on the fireplace 55 above the fire opening;

Fig. 4 is an enlarged detail sectional view approximately on the line 4—4 of Fig. 3;

Fig. 5 is a similar sectional view approximately on the line 5—5 of Fig. 3; and

Fig. 6 is a similar sectional view approximately on the line 6—6 of Fig. 3.

Referring now to the drawings in detail, a fireplace is indicated by the numeral 10, and to the said fireplace is secured a mantel 11. The vertical side members 12 of the 60 mantel are, of course, arranged a suitable distance from the opening in the fireplace, and the shelf 13 disposed a considerable distance above the said opening. The face board between the shelf and side members of 70 the mantel is indicated by the numeral 14, and upon this face board, below the shelf 13 there is approximately centrally secured an outwardly extending spring clip 15. To the inner edges of the members 12 are secured 75 the angle ends of longitudinally disposed spring clips 16 which are directed toward the opening in the fireplace.

The clip 15 has its outer end rounded 80 downwardly to provide a jaw, and the inner edge of the said jaw is rounded upon itself to form a hook 17.

The clips 16 are each formed from a strip of spring metal which is rounded or bent upon itself beyond the center thereof to provide inner and outer contacting portions. These portions are bent at a right angle, and the outer angle portion is secured to the inner faces of the stiles 12 of the mantel. The free ends of the lapping members are 90 bent outwardly to provide jaws 19. The jaws are spaced from each other, the inner jaw being in the nature of a directing element and has its end curved away from the outer jaw. The outer jaw is rounded upon 95 itself in the direction of the inner jaw and has its extremity further rounded upon itself to provide a bead 18.

On the inside of the side members 12 of the mantel 11 slightly above the horizontal 100 lower edge of the tiles at the opening in the fireplace are arranged oppositely disposed outwardly extending brackets 21, the said brackets having offset lower portions that are secured directly to the side members 12. 105

The folding screen includes a flat top plate of non-reticulated material which is indicated by the numeral 22, the same preferably having its edges beaded and reinforcing wires located in the said beads. The ends 110

of the wire in the rear bead extend a suitable distance beyond the side edges of the top plate and are indicated by the numeral 23. The projecting ends 23 of the wire are received in elongated slots 24 in the longitudinal arms of the brackets 21, whereby the top plate is hingedly connected to the brackets but is also permitted a limited sliding movement with respect to the brackets and 10 with respect to the fireplace.

On the outer edge of the top plate 22, a suitable distance inward of the ends thereof are secured outwardly extending rounded straps providing what I will term the ears 15 and which are designated by the numerals 25. These ears receive therethrough the upper bar of the outer or face member of the screen, whereby such member is loosely connected to the top. The outer member of the 20 screen comprises two substantially rectangular frames indicated by the numerals 26 and 27 respectively, the said frames being independent of each other, each being provided with a facing of reticulated material 25 such as crossed wires 28.

Each side of the screen comprises two substantially rectangular frames 29 and 30 respectively. These frames equal in height the front or outer frames but are of a materially less width than the said outer frames. The adjacent edges of the frames 29 and 30 providing the respective sides of the frame are hingedly connected to each other as indicated by the numerals 31, the said hinges 35 being preferably in the nature of straps, and in a like manner the outer edge of the side frames are hingedly connected to the side edge of the front frames as indicated by the numerals 32.

When the device is in operative position the lower edge of the front of the screen rests on the hearth a suitable distance outward of the mantel and fireplace. The sides of the screen extend inwardly so that the inner edges thereof are received between the jaws of the clips 16. This effectively retains the screen in its set up condition. It should have been stated, and is clearly illustrated 45

by the drawings, that the side frames of the screen have secured thereon facings of 5 reticulated material, such as crossed wires, the said facing being indicated by the numerals 33. The slideable top, when the confronting side members of the screen are arranged in active position thereon, permits of 55 a bodily longitudinal movement of the device in the direction of the fire place, so that the inner vertical members of the sides will be directed for proper engagement between the lips for engagement between the spaced lips 60 of the brackets.

When the device is to be folded the side screens are brought out of engagement with the clips and are swung over the front frame. The sections comprising the side 65 frames are then swung against each other, as are the sections comprising the front frame. The folded side frames are then swung against the folded front frames. When in such position the folded screen is 70 swung upwardly of the fireplace and the longitudinal edge, which normally provides the lower member of the lower section of the front frame is engaged by the hook 17 of the horizontally disposed spring clip 15 75 which, in connection with the projecting ends of the wire forming the trunnions 23 that engage with the brackets 21 effectively sustains the screen in its inoperative position below the shelf of the mantel 11.

Having thus described the invention, what is claimed as new, is:—

In combination with a fireplace and a mantel, a bracket located on each side of the fireplace, a sectional folding screen including 85 a swinging top having slideable hinge connections with said brackets, spring clips on the sides of the fireplace engaging adjacent portions of said screen, and a hook above the fireplace adapted to engage and hold the 90 folded screen in elevated position.

In testimony whereof we affix our signatures.

CHARLES A. CANNON.
HARVEY E. SCOTT.
